UNITED STATES PATENT OFFICE.

MAURICE BALLIN, OF LOS GATOS, CALIFORNIA, ASSIGNOR TO NEUSTADTER BROS., OF SAN FRANCISCO, CALIFORNIA, A CORPORATION OF CALIFORNIA.

THREE-WAY POCKET.

Application filed October 18, 1923. Serial No. 669,213.

To all whom it may concern:

Be it known that I, MAURICE BALLIN, a citizen of the United States, residing at Los Gatos, county of Santa Clara, and State of California, have invented new and useful Improvements in a Three-Way Pocket, of which the following is a specification.

This invention relates to a pocket structure and especially to a three-way pocket structure which is particularly adapted to mechanics' outer garments, overalls, shirts, aprons, etc.

The object of the present invention is to generally improve and simplify the construction and operation of pocket structures of the character described; to increase the strength, wearing qualities and utility of the same; to provide a pocket structure which is cheap to manufacture and which may be readily applied to mechanics' garments such as pants, overalls, shirts, aprons and the like; and further, to provide a structure in which, in combination with the garment to which it is attached, will form three separate pockets: first, a pocket for the reception of a note-book or the like; second, a pocket for the reception of a pencil, rule or screw driver, etc., and third, a pocket for the reception of a watch, and in conjunction therewith to provide means for preventing accidental removal of the watch, and to prevent it from falling out when stooping over.

One form which my invention may assume is exemplified in the following description and illustrated in the accompanying drawings, in which—

Fig. 1 is a front view of the pocket structure showing it attached to a portion of a garment.

Fig. 2 shows the blank of the inner pocket section.

Fig. 3 shows the blank of the intermediate pocket section.

Fig. 4 shows the blank of the exterior pocket section.

Referring to the drawings in detail, and particularly to Figs. 2, 3 and 4, A indicates a section of cloth which is substantially rectangular in shape and which is adapted to be stitched along the edges indicated at 2, 3 and 4 to a garment such as an apron, shirt, overalls or the like. The section of cloth indicated at A forms the inner pocket section, while the section of cloth shown at B forms the exterior pocket section. The

blank from which this cloth is cut is also substantially rectangular in shape and of a size equal to the section indicated at A. Notches are, however, cut in the upper and side edges of the section B as shown at 6, 60 7 and 8, and the cloth intermediate the notches is turned inwardly as indicated by dotted lines at 9 and 10 and they are then permanently secured in this position by stitching them to the section B along the dotted lines indicated at 11. The intermediate section of cloth is also rectangular in shape as shown in Fig. 3 and it is notched along the bottom and side edges as indicated at 12 and 13 to permit a section thereof 70 to be folded in under as shown by dotted lines at 14, and the inturned portion is then stitched along the dotted lines indicated at 15 and 16 to secure the folded portion permanently.

When the sections shown in Figs. 3 and 4 have been cut, folded and stitched as shown, it is only necessary to assemble them in the proper manner and to permanently attach them to the garment indicated at C 80 (see Fig. 1) in the following manner:

The inner pocket blank A is first laid on the flat surface. The intermediate section D, shown in Fig. 3, is then placed on top of the pocket blank A, on the upper left-hand corner of the same. The outer pocket blank B is then placed on top of the blanks A and D. The upper edges of the three superposed sections are now turned in and a double line of stitching is run along the upper edge as indicated by the dotted lines 17 and 18. A vertical line of stitching is then run from the point 19 to the point indicated at 20; this line of stitching being indicated by the dotted line 21, and two other 90 V-shaped seams or lines of stitching are applied as indicated by the dotted lines 22, 23, 24 and 25. The pocket blank sections are in this manner assembled and secured with relation to each other and are now ready to be 100 applied to the garment. This is accomplished by turning in the outer edges 26 and 27 and the lower edge 28, and by running a double line of stitching along the side edges and the bottom edge as indicated by 105 the dotted lines 29, 30 and 31. The double line of stitching indicated by the dotted lines 29, 30 and 31 passes through the superposed pocket sections and also through the cloth

110 C of the garment, thus permanently attach-

ing the pocket sections to the garment. This completes the operation and as will be seen three pockets are formed. One main pocket is formed between the innermost pocket section A and the cloth of the garment C. This pocket is employed for the reception of a note-book or the like. Two pockets are formed between the inner blank A and the exterior blank B, one pocket being long and narrow, and the other of a similar length but wider.

The entrance to the long and narrow pocket is indicated at 32 and this pocket is employed for the purpose of receiving a pencil, ruler, screw driver, or the like, said long narrow pocket being formed between the stitching indicated at 21 and the side stitching indicated at 30. The third pocket, the entrance of which is indicated at 33, is employed for the reception of a watch. It has a length equal to the pencil or rule receiving pocket, but it is wider as previously stated as it is formed between the line of stitching indicated at 21 and the side stitching indicated at 29. The entrance to both the pockets 32 and 33 is inclined as indicated by the lines 34 and 35 and these inclined entering edges or openings are formed by the folded flaps 9 and 10 of the blank B. The V-shaped stitching indicated at 22, 23, 24 and 25 cooperates with the watch receiving pocket and tapers down or narrows the opening thereto. It at the same time forms inserts or corners in which the watch would very likely lodge if the wearer of the garment should stoop or otherwise, thus preventing the watch from accidentally dropping out. Other means are, however, employed for the purpose of preventing the watch from dropping or falling out and for preventing accidental removal of the same, this means being the intermediate blank section D. It, as previously stated, is attached to the inner blank A by the side stitching 29 and by the V-shaped stitching indicated by the dotted lines 22, 23, 24 and 25, and the blank itself is provided with an inturned flap such as shown at 14 which is stitched upon itself along the dotted lines indicated at 15 and 16. The edge of the folded portion of the intermediate blank D is indicated by the full line 40, in Fig. 3, and by the long dotted line 41 in Fig. 1. This edge is free with relation to the inner blank A as it is not stitched thereto and a recess or pocket is thus formed between the lines indicated at 18, 22, 24 and 29; the entrance to the pocket being under the folded edge 40 and which is again indicated by the dotted line 41. In other words, if the wearer should assume a position where the watch might tend to fall out, it would very likely slide in under the flap 14 or in under the free edge 40 and would thus enter the space or pocket formed between the blank D and the inner

blank A. There are, therefore, three pockets or recesses into which the watch could fall if the garment were turned to a position where the watch might fall, and the chances are therefore very small that the watch would drop out of the main entrance to the pocket indicated at 33. A safety pocket for the watch is thus provided; a convenient pocket for the reception of rules, pencils, etc., and also a pocket for the reception of a note-book or the like.

The upper line of stitching indicated at 18 does not pass through the cloth of the garment indicated at C and this edge is thus free with relation to the garment and forms the entrance to the innermost pocket which is provided for the reception of a note-book.

While certain features of the present invention are more or less specifically illustrated, I wish it understood that various changes in form and proportion may be resorted to within the scope of the appended claims. I similarly wish it understood that the materials and finish of the several parts employed may be such as the experience and judgment of the manufacturer may dictate or various uses may demand.

Having thus described my invention, what I claim and desire to secure by Letters Patent is—

1. The combination with a garment, of a three-way pocket therefor, said pocket consisting of an inner blank and an outer blank, the inner blank being stitched along the bottom and side edges to the garment to form a note-book pocket, and the outer blank being stitched along the bottom and sides to the inner blank and the garment and along a portion of its upper edge to the upper edge of the inner blank only, said outer blank being also stitched substantially centrally and vertically to the inner blank only to form a rule receiving pocket and a watch pocket, and an inturned flap on each side of the outer blank and at the upper end thereof, said inturned flaps being stitched to the outer blank to form slanting entrance openings to the last named pockets and a substantially triangular shaped flap stitched at its top and side edge to one corner of the inner blank and having a free angular edge extending in under one of the inturned flaps of the outer blank.

2. The combination with a garment, of a three-way pocket therefor, said pocket consisting of an inner blank and an outer blank, the inner blank being stitched along the bottom and side edges to the garment to form a note-book pocket, and the outer blank being stitched along the bottom and sides to the inner blank and the garment and along a portion of its upper edge to the upper edge of the inner blank only, said outer blank being also stitched substantially centrally

and vertically to the inner blank only to form a rule receiving pocket and a watch pocket, and an intermediate blank disposed in the upper right hand corner of the inner blank and placed between the inner blank and the outer blank, said intermediate blank being stitched along one side to the inner blank and the garment, and being stitched along its upper edge to the upper edge of the inner blank only, said intermediate blank being provided with an inturned flap which is formed on its right hand lower corner and which is stitched upon itself, and said intermediate blank being also provided with two V-shaped lines of stitching, one in the lower left hand corner and one in the upper right hand corner, said V-shaped stitching passing through the inner, the outer and the intermediate blank.

20 3. The combination with a garment, of a
three-way pocket therefor, said pocket con-
sisting of an inner blank and an outer blank,
the inner blank being stitched along the bot-
tom and side edges to the garment to form a
25 note-book pocket, and the outer blank being
stitched along the bottom and sides to the
inner blank and the garment and along a
portion of its upper edge to the upper edge
of the inner blank only, said outer blank
30 being also stitched substantially centrally
and vertically to the inner blank only to
form a rule receiving pocket and a watch
pocket, an inturned flap on each side of the
outer blank and at the upper end thereof,

35 said inturned flaps being stitched to the outer blank to form slanting entrance openings to the last named pockets, and means disposed in the entrance of the watch pocket for preventing accidental removal of a watch. 40

4. The combination with a garment, of a three-way pocket therefor, said pocket consisting of an inner blank and an outer blank, the inner blank being stitched along the bottom and side edges to the garment to form a note-book pocket, and the outer blank being stitched along the bottom and sides to the inner blank and the garment and along a portion of its upper edge to the upper edge of the inner blank only, said outer blank being also stitched substantially centrally and vertically to the inner blank only to form a rule receiving pocket and a watch pocket, an inturned flap on each side of the outer blank and at the upper end thereof, said inturned flaps being stitched to the outer blank to form slanting entrance openings to the last named pockets, and means disposed in the entrance of the watch pocket for preventing accidental removal of a watch, said means comprising a substantially triangular shaped closing flap stitched along its top and side edges to one corner of the inner blank and having its angular edge free, said angular edge being wholly covered by the left hand inturned flap of the outer blank.

MAURICE BALLIN.
